WASHING MACHINE AGITATOR

Russell W. Carter, Albia, Iowa

Application December 13, 1934, Serial No. 757,257

3 Claims. (Cl. 259—101)

This invention has reference to agitators for washing machines, more particularly to an agitator having means for adjusting the effective area of the fluid agitating portions whereby the 5 agitator may be adjusted to suit the particular use to which it is to be put.

It is well known that the majority of modern washing machines are equipped with an agitator or dolly of the so-called submerged type, which 10 conventionally comprises a base portion having a central upstanding stem or conical portion, the same having a plurality of vanes disposed thereon in such a manner that when the agitator is alternately rotated in opposite directions in water 15 the vanes cause more or less violent agitative movements in the water.

Washing machines of the type using the form of agitator here considered are thought sufficiently well known to make description unnecessary 20 further than to say that the present agitator is adapted to be used with any of the conventional types.

In practical use the agitator is disposed adjacent the bottom of the tub and alternately rotated in opposite directions to agitate the liquid in the tub whereby garments placed in the liquid 25 are agitated therein and washed.

Obviously, during ordinary washing activity 30 there are times when the garments being washed consist of comparatively light, small pieces and to agitate and wash these in the most efficient manner a certain type or magnitude of agitation is required, whereas at other times it may be desired to wash heavy articles such as work trousers, 35 rugs, quilts or the like and for this latter purpose another type or magnitude of agitation is required for best washing results.

Since all agitation produced by a washing 40 mechanism is provided by the vanes on the agitator, it is but logical to assume that the simplest and most effective way to render an agitator capable of most efficiently washing articles of different kinds is to provide means for adjusting the area of the vanes which act upon the liquid 45 and articles.

The object of this invention is to provide means for adjusting the area of the vanes for the purpose above noted.

Referring to the accompanying drawing;

Fig. 1 is an elevational view of my agitator with portions broken away and certain associated parts removed;

Fig. 2 is a plan view of the same showing dotted outline of interior parts and a small portion 55 broken away to permit clearer description;

Fig. 3 is a sectional elevational view taken on line 3—3 in Fig. 2; and

Fig. 4 is a sectional elevational view taken on line 4—4 in Fig. 2.

The several views illustrate my invention as 5 comprising a foundation agitator member 10 having a circular base portion 11, a plurality of upstanding vanes 12 and a central upstanding tubular portion 13.

Adapted to sleeve over the foundation member 10 is a member 14 having a tubular central portion 15 and radially extending hollow portions 16 adapted to enclose the vanes 12.

Interior of the stem 15 is a threaded portion 17, Fig. 3 and disposed between stem 15 and 15 tubular portion 13 is a sleeve member 18 having an external threaded portion 19 engaged with threads 17 and an enlarged shoulder portion 20 at its upper end.

The lower end of sleeve 18 rests upon the upper 20 edge of vanes 12 and it is confined in this position by means of a collar 21 affixed to the upper end of tubular portion 13.

By means of the shoulder 20, sleeve 18 is manually rotated whereupon threads 19, engaged with 25 threads 17, bring about vertical movement of member 14 to elevate the vane portions 16 as indicated in dotted lines in Fig. 3. Such movement 30 obviously extends the effective working area of the vanes and by adjusting the position of member 14 the agitative action of the mechanism may be modified to suit the conditions of practical use.

To permit free movement of member 14 upon the vanes 12 without excessive looseness, I preferably so proportion the portions 16 as to leave a space 23, Figs. 3 and 4, between the interior walls of portions 16 and the surfaces of vanes 12. Adjacent the interior lower edge of at least one of members 16 the material thereof is fashioned 40 to have inwardly directed portions 24 having a relatively small area in contact with the surface of the vane. The relatively small contacting surfaces are easily fitted to operate with a minimum of friction which would obviously not be the case 45 if the entire surface areas were in contact.

Interiorly of the upper end of stem 13 there is provided an opening 22 of any desired form adapted to receive, in keyed relation, the upper 50 end of a conventional agitator driving shaft.

Numerous modifications of the structure herein disclosed are possible without alteration of the principle of my invention. I do not wish to be limited except within the scope of the appended 55 claims.

What I claim is:

1. An agitator of the class described having in combination a member comprising a base portion, a centrally disposed upstanding tubular portion and a plurality of upstanding vanes, a second member having vane portions fashioned to telescopically fit over the first named vanes and having a central upstanding tubular portion adapted to surround the first mentioned tubular member, the latter having threads formed in its interior surface, a sleeve member surrounding the first tubular portion and disposed between the first and second tubular portions, said sleeve having a threaded portion engaging the threads of the second tubular portion whereby rotation of said sleeve brings about telescopic movement of the second named vane portions upon the first named vane portions.

2. In a submerged washing machine agitator,

a base member, vertical vanes on said base, a central drive post attached to said base extending above the water line, a rotatable sleeve over said drive post, a hand grip on the top of said sleeve, a threaded lower section on said sleeve, an adjustable vane member mounted on the threaded section of the sleeve with vanes telescoping the vanes on the base member whereby the height of the vanes may be adjusted by the hand grip on the top of the sleeve member.

3. In a submerged washing machine agitator, a submerged base, vanes on said base adjustable in height, a drive stem on said base extending above the water line, a hand grip mounted near the top of the stem above the water line, and means to adjust the height of the vanes by rotation of the hand grip.

RUSSELL W. CARTER.
